I. Warren,

Inhaler.

No 8,813.

Patented Mar 16, 1852.

Fig. 2.

Fig. 1.

UNITED STATES PATENT OFFICE.

IRA WARREN, OF BOSTON, MASSACHUSETTS.

INSTRUMENT FOR INHALING POWDERS.

Specification of Letters Patent No. 8,813, dated March 16, 1852.

To all whom it may concern:

Be it known that I, IRA WARREN, of Boston, in the county of Suffolk and State of Massachusetts, have invented a new and useful instrument which I call a "Powder-Inhaler," with which to inhale certain medicinal powders, &c., into the throat and lungs, and that the following description, taken in connection with the accompanying drawings, hereinafter referred to, forms a full and exact specification of the same, wherein I have set forth the nature and principles of my said invention by which it may be distinguished from others of a similar class, together with such parts as I claim and desire to have secured to me by Letters Patent.

The figures of the accompanying plate of drawings represent my powder inhaler.

Figure 1 is a plan or top view of the same, and Fig. 2 is a longitudinal vertical section taken in the plane of the line A B, Fig. 1.

My instrument or powder inhaler is designed for the purpose of inhaling medicine into the throat and lungs, and, at the same time, to prevent any of the said medicine from lodging in the mouth.

a a represents a tube constructed of any proper material of the shape shown in the drawings having a collar *b b* fastened to its

larger end. Into this tube *a a* is inserted a receiver *c c* somewhat in the shape of a tube vial, having its lower end or bulb pierced with fine holes. This tube has shoulders *d d'* which bear against the outside and inside respectively of the collar *b b*. The powder is put into the receiver which with its exterior tube *a a* is introduced into the mouth, the powder being sifted through the holes of the receiver while breathing, by twirling the said receiver, the exterior tube *a a* preventing any of the powder from lodging in the mouth.

Having thus described my powder inhaler I shall state my claim as follows:—

What I claim as my invention and desire to have secured to me by Letters Patent is—

The instrument above described for inhaling powder &c. into the throat and lungs, the said instrument consisting of a receiver with holes in its bulb or end, covered by, and working loosely in, an exterior tube, which prevents any of the medicine from lodging in the mouth, substantially as above described.

IRA WARREN.
